UNITED STATES PATENT OFFICE.

JULES GERSANT, OF CLAPHAM, LONDON, AND GEORGES JUSTIN JOSEPH LEGRAND, OF LANCING, ENGLAND.

TURBINE.

No. 857,048.

Specification of Letters Patent.

Patented June 18, 1907.

Application filed June 30, 1906. Serial No. 324,292.

To all whom it may concern:

Be it known that we, JULES GERSANT, a citizen of France, residing at Clapham, in the county of London, England, and GEORGES JUSTIN JOSEPH LEGRAND, a citizen of France, residing at Lancing, in the county of Sussex, England, have invented new and useful Improvements in Turbines, of which the following is a specification.

This invention relates to improvements in rotary motors or turbines. According to same, steam or other fluid is caused to pass into a curved or elbow-shaped slot or opening in a fixed diaphragm or part in a cylinder, thence into an obliquely arranged curved or elbowed slot in a part secured on a rotatable shaft, thence into a further slot in a similar fixed diaphragm or part similar in shape to the first one, thence out of the cylinder at the far end, through an obliquely arranged passage or pipe and into the cylinder at the first end again whence it passes into the next slot or opening in the first fixed part through the second slot or opening in the rotatable part, through the next slot or opening in the second fixed part and so on to a further oblique passage or pipe to the first end again, the operation being repeated until the whole circle of the cylinder and the series of openings in each part has been traversed and the exhaust reached.

In the drawings which illustrate one means for carrying the invention into effect—

Figure 1, is a longitudinal elevation partly in section on line $w-w$ Fig. 2. Fig. 2, is a sectional elevation on line $v-v$ Fig. 1. Fig. 3, is a sectional elevation on line $y-y$ Fig. 1. Fig. 4, is a diagrammatic view showing the direction taken by the motive fluid, and, Fig. 5, is a section on line $x-x$ Fig. 2, showing the construction of the opening of the inlet or exhaust opening and of the wall passages to the fixed diaphragm.

The motor may consist of two concentric cylinders, the space between being divided into a number of separate compartments preferably arranged obliquely around the walls or as shown in the drawings the cylinder a is provided with a series of oblique passages running the whole length of the cylinder on the outside. Each of these passages, with the exception of the two uppermost, to which the inlet and exhaust pipes c and d are

connected has two ports i formed in the wall of the cylinder, one at either end thereof.

The cylinder which may be of any suitable length is provided with a fixed diaphragm, drum or part e at each end, each of such diaphragms being provided with a series of curved straight through openings. As shown in Fig. 4, of the drawings the parts e are formed in their outer half g with one opening to two openings h in the inner half, the divisions may, however, be varied as desired. The openings g are adapted to register with the ports i in the wall of the cylinder, while the intermediate diaphragms f , secured to the cylinder a , which may be employed to any number have straight through openings h only. A further series of diaphragms, drums or parts j arranged alternately with the fixed diaphragms f are secured to the central shaft k to be driven so as to permit of their free rotation, within the cylinder a . These latter diaphragms are provided with a series of similarly curved but obliquely arranged openings l adapted to register with the straight through openings in the fixed diaphragms arranged on either side thereof.

The operation of the motor is as follows:— Assuming that the motive fluid is entering the cylinder through the pipe c , it will then pass into the division indicated on Fig. 2, by g^x in communication therewith thence through the passage or passages h^x to the obliquely arranged passages l in the adjacent rotating diaphragm thence through the corresponding straight through passages in the next diaphragm and so on as indicated by the arrows in Figs. 2, and 4, until the division g at the other end is reached, which division opens into the port i at the end of the passage b^x , through said passage into the division g^o and so on until the port i in the passage b^l is reached, to which passage the exhaust pipe d is connected.

Although the passages in the fixed and movable diaphragms, drums or parts are shown substantially radially curved, they may be of any other convenient shape, such as elbowed, so as to obtain the maximum operating surface and also so that the passages in the movable diaphragms in passing those in the fixed ones may do so with their edges more or less parallel to each other which would not be the case with straight radial

passages. It is also obvious that the passages may be formed by means of vanes on the exterior of the rotating part and the interior of the cylinder respectively.

5 If it is desired to reverse the direction of rotation of the shaft *k* it is only necessary to make the exhaust the inlet and vice versa. Any suitable valve gear may be provided for effecting this result and for otherwise controlling the supply of motive fluid, that shown in the drawings being given by way of illustration.

Having now particularly described and ascertained the nature of our said invention 15 and in what manner the same is to be performed, we declare that what we claim is;

1. A turbine comprising a cylinder containing two fixed parts and one intermediate rotatable part all with motive fluid passages 20 of uniform dimensions therethrough, a plurality of channels each in sequence connecting one or more of a series of motive fluid ports in one of the fixed parts to one or more ports adjacent to the corresponding ports in 25 the other fixed part, and motive fluid supply and exhaust passages one connected to one end of the sequence of connected channels and ports and the other to the other end of said sequence.

30 2. A turbine comprising a cylinder containing two fixed parts and one intermediate rotatable part all with motive fluid passages of uniform dimensions therethrough, a plurality of channels formed in one with the cylinder and each in sequence connecting one or 35 more of a series of motive fluid ports in one of the fixed parts to one or more ports adjacent to the corresponding ports in the other fixed part, and motive fluid supply and exhaust 40 passages one connected to one end of the sequence of connected channels and ports and the other to the other end of such sequence.

3. A turbine comprising a cylinder containing two fixed parts and one intermediate 45 rotatable part all with motive fluid passages of uniform dimensions therethrough, a plurality of channels formed between the cylinder and a second concentric cylinder and each in sequence connecting one or more of a 50 series of motive fluid ports in one of the fixed parts to one or more ports adjacent to the corresponding ports in the other fixed part, and motive fluid supply and exhaust 55 passages one connected to one end of the sequence of connected channels and ports and the other to the other end of said sequence.

4. A turbine comprising a cylinder containing two fixed parts and one intermediate rotatable part all with radial passages there- 60 through so shaped as to open and close approximately uniformly throughout their length, a plurality of channels each in sequence connecting one or more of a series of motive fluid ports in one of the fixed parts to one or more ports adjacent to the corresponding 65 ports in the other fixed part, and motive fluid supply and exhaust passages one connected to one end of the sequence of connected channels and ports and the other to

one or more ports adjacent to the corresponding ports in the other fixed part, and motive fluid supply and exhaust passages one connected to one end of the sequence of connected channels and ports and the other to the other end of said sequence. 70

5. A turbine comprising a cylinder containing two fixed parts and one intermediate rotatable part all with motive fluid passages therethrough, a plurality of channels each in sequence connecting one or more of a series 75 of motive fluid ports in one of the fixed parts to one or more ports adjacent to the corresponding ports in the other fixed part, and motive fluid supply and exhaust passages one connected to one end of the sequence of 80 connected channels and ports and the other to the other end of said sequence, and means for reversing the connections of such supply and exhaust passages.

6. A turbine comprising a cylinder containing two fixed parts and one intermediate rotatable part all with radial passages therethrough so shaped as to open and close approximately uniformly throughout their length, a plurality of channels formed in one 90 with the cylinder and each in sequence connecting one or more of a series of motive fluid ports in one of the fixed parts to one or more ports adjacent to the corresponding ports in the other fixed part, and motive fluid 95 supply and exhaust passages one connected to one end of the sequence of connected channels and ports and the other to the other end of said sequence.

7. A turbine comprising a cylinder containing two fixed parts and one intermediate rotatable part all with radial passages therethrough so shaped as to open and close approximately uniformly throughout their length, a plurality of channels formed between the cylinder and a second concentric cylinder and each in sequence connecting one or more of a series of motive fluid ports in one of the fixed parts to one or more ports adjacent to the corresponding ports in the other fixed part, and motive fluid supply and exhaust 105 passages one connected to one end of the sequence of connected channels and ports and the other to the other end of said sequence. 110

8. A turbine comprising a cylinder containing two fixed parts and one intermediate rotatable part all with radial passages therethrough so shaped as to open and close approximately uniformly throughout their 120 length, a plurality of channels each in sequence connecting one or more of a series of motive fluid ports in one of the fixed parts to one or more ports adjacent to the corresponding ports in the other fixed part, and motive 125 fluid supply and exhaust passages one connected to one end of the sequence of connected channels and ports and the other to

the other end of said sequence, and means for reversing the connections of such supply and exhaust passages.

9. A turbine comprising a cylinder containing two fixed parts and one intermediate rotatable part all with motive fluid passages therethrough, a plurality of channels formed between the cylinder and a second concentric cylinder and each in sequence connecting one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

10. A turbine comprising a cylinder containing two fixed parts and one intermediate rotatable part all with radial passages therethrough so shaped as to open and close approximately uniformly throughout their length, a plurality of channels formed in one with the cylinder and each in sequence connecting one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

11. A turbine comprising a cylinder containing two fixed parts and one intermediate rotatable part all with radial passages therethrough so shaped as to open and close approximately uniformly throughout their length, a plurality of channels formed between the cylinder and a second concentric cylinder and each in sequence connecting one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

12. A turbine comprising a cylinder containing two fixed parts and one intermediate rotatable part all with radial passages therethrough so shaped as to open and close approximately uniformly throughout their length, a plurality of channels each in sequence connecting one or more of a series of motive fluid ports in one of the fixed parts to one or more ports adjacent to the corresponding ports in the other fixed part, and motive fluid supply and exhaust passages one connected to one end of the sequence of con-

nected channels and ports and the other to the other end of said sequence, and means for reversing the connections of such supply and exhaust passages.

13. A turbine comprising a cylinder containing a plurality of alternately fixed and rotatable parts with motive fluid passages of uniform dimensions therethrough, a plurality of channels each in sequence connecting one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

14. A turbine comprising a cylinder containing a plurality of alternately fixed and rotatable parts with motive fluid passages of uniform dimensions therethrough, a plurality of channels formed in one with the cylinder and each in sequence connecting one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

15. A turbine comprising a cylinder containing a plurality of fixed and rotatable parts with motive fluid passages of uniform dimensions therethrough, a plurality of channels formed between the cylinder and a second concentric cylinder and each in sequence connecting one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

16. A turbine comprising a cylinder containing a plurality of alternately fixed and rotatable parts with radial passages therethrough so shaped as to open and close approximately uniformly throughout their length, a plurality of channels each in sequence connecting one or more of a series of motive fluid ports in a fixed part in one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

17. A turbine comprising a cylinder containing a plurality of alternately fixed and rotatable parts with motive fluid passages

therethrough, a plurality of channels each in sequence connecting one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence, and means for reversing the connections of such supply and exhaust passages.

18. A turbine comprising a cylinder containing a plurality of alternately fixed and 15 rotatable parts with radial passages therethrough so shaped as to open and close approximately uniformly throughout their length, a plurality of channels formed in one with the cylinder and each in sequence connecting one or more of a series of motive fluid ports in a fixed part at one end of the cylinder to one or more ports adjacent to the corresponding ports in a fixed part at the other end of the cylinder, and motive fluid 20 supply and exhaust passages one connected to one end of the sequence of connected channels and ports and the other to the other end of said sequence.

19. A turbine comprising a cylinder containing a plurality of alternately fixed and 30 rotatable parts with radial passages therethrough so shaped as to open and close approximately uniformly throughout their length, a plurality of channels formed between the cylinder and a second concentric cylinder and each in sequence connecting one or more of a series of motive fluid ports in a fixed part at one end of the cylinder to one or more ports adjacent to the corresponding ports in a fixed part at the other end of the cylinder, and motive fluid supply and exhaust passages one connected to one 35 end of the sequence of connected channels and ports and the other to the other end of said sequence.

20. A turbine comprising a cylinder containing a plurality of alternately fixed and 40 rotatable parts with radial passages therethrough so shaped as to open and close approximately uniformly throughout their length, a plurality of channels each in sequence connecting one or more of a series of motive fluid ports in a fixed part at one end of the cylinder to one or more ports adjacent to the corresponding ports in a fixed part at the opposite end of the cylinder, and motive fluid supply and exhaust passages one connected to one 45 end of the sequence of connected channels and ports and the other to the other end of said sequence, and means for reversing the connections of such supply and exhaust passages.

21. A turbine comprising a cylinder containing a plurality of alternately fixed and 50 rotatable parts with motive fluid passages

therethrough, a plurality of channels formed between the cylinder and a second concentric cylinder and each in sequence connecting one or more of a series of motive fluid ports in a fixed part at one end of the cylinder to one or more ports adjacent to the corresponding ports in a fixed part at the opposite end of the cylinder, and motive fluid supply and exhaust passages one connected to one end of the sequence of connected channels and 55 ports and the other to the other end of said sequence, and means for reversing the connections of such supply and exhaust passages.

22. A turbine comprising a cylinder containing a plurality of alternately fixed and 60 rotatable parts with radial passages therethrough so shaped as to open and close approximately uniformly throughout their length, a plurality of channels formed in one with the cylinder and each in sequence connecting one or more of a series of motive fluid ports in a fixed part at one end of the cylinder to one or more ports adjacent to the corresponding ports in a fixed part at the opposite end of the cylinder, and motive fluid supply and exhaust passages one connected to one 65 end of the sequence of connected channels and ports and the other to the other end of said sequence, and means for reversing the connections of such supply and exhaust passages.

23. A turbine comprising a cylinder containing a plurality of alternately fixed and 70 rotatable parts with radial passages therethrough so shaped as to open and close approximately uniformly throughout their length, a plurality of channels formed between the cylinder and a second concentric cylinder and each in sequence connecting one or more of a series of motive fluid ports in a fixed part at one end of the cylinder to one or more ports adjacent to the corresponding ports in a fixed part at the opposite end of the cylinder, and motive fluid supply and exhaust 75 passages one connected to one end of the sequence of connected channels and ports and the other to the other end of said sequence, and means for reversing the connections of such supply and exhaust passages.

24. A turbine comprising a cylinder containing a plurality of alternately fixed and 80 rotatable parts with radial passages therethrough so shaped as to open and close approximately uniformly throughout their length, a plurality of channels each in sequence connecting one or more of a series of motive fluid ports in a fixed part at one end of the cylinder to one or more ports adjacent to the corresponding ports in a fixed part at the opposite end of the cylinder, and motive fluid supply and exhaust 85 passages one connected to one end of the sequence of connected channels and ports and the other to the other end of said sequence, and means for reversing the connections of such supply and exhaust passages.

other end of said sequence, and means for reversing the connections of such supply and exhaust passages.

25. A turbine comprising a cylinder containing two fixed parts and one intermediate rotatable part all with motive fluid passages of uniform dimensions therethrough, a plurality of channels each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence.

26. A turbine comprising a cylinder containing two fixed parts and one intermediate rotatable part all with motive fluid passages of uniform dimensions therethrough, a plurality of channels formed in one with the cylinder and each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of such sequence.

27. A turbine comprising a cylinder containing two fixed parts and one intermediate rotatable part all with motive fluid passages of uniform dimensions therethrough, a plurality of channels formed between the cylinder and a second concentric cylinder and each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence.

28. A turbine comprising a cylinder containing two fixed parts and one intermediate rotatable part all with radial passages therethrough so shaped as to open and close approximately uniformly throughout their length, a plurality of channels each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of the said sequence.

29. A turbine comprising a cylinder containing two fixed parts and one intermediate rotatable part all with motive fluid passages therethrough, a plurality of channels each in

sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

30. A turbine comprising a cylinder containing two fixed parts and one intermediate rotatable part all with radial passages therethrough so shaped as to open and close approximately uniformly throughout their length, a plurality of channels formed in one with the cylinder and each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence.

31. A turbine comprising a cylinder containing two fixed parts and one intermediate rotatable part all with radial passages therethrough so shaped as to open and close approximately uniformly throughout their length, a plurality of channels formed between the cylinder and a second concentric cylinder and each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence.

32. A turbine comprising a cylinder containing two fixed parts and one intermediate rotatable part all with radial passages therethrough so shaped as to open and close approximately uniformly throughout their length, a plurality of channels each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

33. A turbine comprising a cylinder containing two fixed parts and one intermediate rotatable part all with motive fluid passages therethrough, and a plurality of channels formed between the cylinder and a second

cylinder and each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

34. A turbine comprising a cylinder containing two fixed parts and one intermediate rotatable part all with radial passages therethrough so shaped as to open and close approximately uniformly throughout their length, a plurality of channels formed in one with the cylinder and each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

35. A turbine comprising a cylinder containing two fixed parts and one intermediate rotatable part all with radial passages therethrough so shaped as to open and close approximately uniformly throughout their length, a plurality of channels formed between the cylinder and a second concentric cylinder and each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

36. A turbine comprising a cylinder containing two fixed parts and one intermediate rotatable part all with radial passages therethrough so shaped as to open and close approximately uniformly throughout their length, a plurality of channels each in sequence connecting through motive fluid chambers one or more of a series of motive fluid ports in one of the fixed parts to one or more ports adjacent to the corresponding ports in the other fixed part, and motive fluid supply and exhaust passages one connected to one end of the sequence of connected channels and ports and the other to the other end of said sequence, and means for reversing the connections of such supply and exhaust passages.

37. A turbine comprising a cylinder con-

taining a plurality of alternately fixed and rotatable parts with motive fluid passages of uniform dimensions therethrough, a plurality of channels each in sequence connecting through motive fluid chambers one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

38. A turbine comprising a cylinder containing a plurality of alternately fixed and rotatable parts with motive fluid passages of uniform dimensions therethrough, a plurality of channels formed in one with the cylinder and each in sequence connecting through motive fluid chambers one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

39. A turbine comprising a cylinder containing a plurality of fixed and rotatable parts with motive fluid passages of uniform dimensions therethrough, a plurality of channels formed between the cylinder and a second concentric cylinder and each in sequence connecting through motive fluid chambers one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

40. A turbine comprising a cylinder containing a plurality of alternately fixed and rotatable parts with radial passages therethrough so shaped as to open and close approximately uniformly throughout their length, a plurality of channels each in sequence connecting through motive fluid chambers one or more of a series of motive fluid ports in a fixed part in one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

41. A turbine comprising a cylinder containing a plurality of alternately fixed and rotatable parts with motive fluid passages therethrough, a plurality of channels each in

sequence connecting through motive fluid chambers one or more of a series of motive fluid ports in a fixed part at one end of the cylinder to one or more ports adjacent to the 5. corresponding ports in a fixed part at the other end of the cylinder, and motive fluid supply and exhaust passages one connected to one end of the sequence of connected channels and ports and the other to the other end 10 of said sequence, and means for reversing the connections of such supply and exhaust passages.

42. A turbine comprising a cylinder containing a plurality of alternately fixed and rotatable parts with radial passages therethrough so shaped as to open and close approximately uniformly throughout their length, a plurality of channels formed in one with the cylinder and each in sequence connecting through motive fluid chambers one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence.

30 43. A turbine comprising a cylinder containing a plurality of alternately fixed and rotatable parts with radial passages therethrough so shaped as to open and close approximately uniformly throughout their length, a plurality of channels formed between the cylinder and a second concentric cylinder and each in sequence connecting through motive fluid chambers one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other 45 to the other end of said sequence.

44. A turbine comprising a cylinder containing a plurality of alternately fixed and rotatable parts with radial passages therethrough so shaped as to open and close approximately uniformly throughout their length, a plurality of channels each in sequence connecting through motive fluid chambers one or more of a series of motive fluid ports in a fixed part at one end of the cylinder to one or more ports adjacent to the corresponding ports in a fixed part at the other end of the cylinder, and motive fluid supply and exhaust passages one connected to one end of the sequence of connected channels and ports and the other to the other end of said sequence, and means for reversing the connections of such supply and exhaust passages.

45. A turbine comprising a cylinder con-

taining a plurality of alternately fixed and 65 rotatable parts with motive fluid passages therethrough, a plurality of channels formed between the cylinder and a second concentric cylinder and each in sequence connecting through motive fluid chambers one or more 70 of a series of motive fluid ports in a fixed part at one end of the cylinder to one or more ports adjacent to the corresponding ports in a fixed part at the opposite end of the cylinder, and motive fluid supply and exhaust 75 passages one connected to one end of the sequence of connected channels and ports and the other to the other end of said sequence, and means for reversing the connections of such supply and exhaust passages. 80

46. A turbine comprising a cylinder containing a plurality of alternately fixed and rotatable parts with radial passages therethrough so shaped as to open and close approximately uniformly throughout their length, a plurality of channels formed in one with the cylinder and each in sequence connecting through motive fluid chambers one or more of a series of motive fluid ports in a fixed part at one end of the cylinder to one or more ports adjacent to the corresponding ports in a fixed part at the opposite end of the cylinder, and motive fluid supply and exhaust passages one connected to one end of the sequence of connected channels and ports and the other to the other end of said sequence, and means for reversing the connections of such supply and exhaust passages. 85
